UNITED STATES PATENT OFFICE.

ERNEST W. MOIR, OF LONDON, ENGLAND, ASSIGNOR TO S. PEARSON AND SON, INCORPORATED, OF LONG ISLAND CITY, NEW YORK, A CORPORATION OF NEW YORK.

APPARATUS FOR ERECTING TUNNELS.

SPECIFICATION forming part of Letters Patent No. 794,635, dated July 11, 1905.

Application filed March 18, 1905. Serial No. 250,786.

To all whom it may concern:

Be it known that I, ERNEST W. MOIR, a subject of the King of Great Britain and Ireland, residing in London, England, have invented 5 a Improved Apparatus for Erecting Tunnels, of which the following is a specification.

My invention relates more particularly to the construction of apparatus for use in the building of tunnels, such as employed by me 10 in the first Hudson river tunnel, as illustrated and described in the *Journal of the London Society of Arts* for May 15, 1896, Vol. XLIV, pages 567 and 584. Characteristic features of 15 that apparatus were the construction of the lining of the tunnel of iron segments and the putting of these segments into place as the work progressed by means of a hydraulic erector mounted upon a stage traveling on rails which were carried by brackets secured to the 20 erected tunnel-lining.

The main object of my present invention is to improve the construction and operation of such an erector apparatus.

In the accompanying drawings, Figure 1 is 25 a transverse section of a tunnel with such an apparatus embodying my improvements. Fig. 2 is a longitudinal section of the same, and Fig. 3 is an enlarged view of some details.

Referring to Figs. 1 and 2, A A are the metallic segments which are fitted together to 30 form the finished tubular lining of the tunnel, and B B are brackets which are bolted at a suitable height to the flanges of the segments of which the finished lining has been built up. 35 On these brackets are mounted rails D D, on which travel the wheels of the erector-stage C, carrying the hydraulic-erector mechanism intended to handle the segments to be put into place. This hydraulic erector comprises a 40 foundation-plate 4, secured to the forward side of the traveling stage C and providing a bearing for a rotary plate 5, with pinion 6, into which gears a rack 7 on a piston-rod 8 with a piston working in the hydraulic cylinder 9, 45 mounted on the stage C. On the plate 5 there is mounted to slide in transverse guides a lifting-arm or erector-bar 10, operated by a piston-rod 11, which is secured to the bar at 12

and which has a piston working in a hydraulic cylinder 13. The means for attaching the 5 segments to the outer end of the lifting-arm 10 may be those forming the subject of my Patent No. 780,804; but according to my present invention I reduce the required extent of rotary motion of the erecting-arm on the foundation-plate 4, and at the same time I counter-balance the device better by making the arm 10 double-ended—that is, extending nearly across the tunnel—so that as convenience may 55 require a segment A to be put into place may 60 be attached to either end of the arm or bar 10.

In order to facilitate the advance of the erecting-stage C as the lining is put in place, I provide on the brackets B B, on each side of the tunnel, two adjacent rails D D', and 65 the stage itself is provided on each side with wide wheels E E to rest on either rail or both rails. As will be seen by reference to Fig. 3, double-rail chairs F are provided on each 70 bracket B, and while one rail D may be secured in the chair by means comparatively permanent the other rail D' is secured in the chair by means which can be easily operated to drop the rail from supporting contact with the wheels, so that such rail can then be 75 moved lengthwise. In the drawings I have shown the chairs F as provided with wedges G, which can be driven into the chairs transversely under the rail D'. Thus when the forward end of the traveling stage has to be 80 advanced beyond the forward ends of what I may term the "permanent" rails D the wedges G G are withdrawn sufficiently to let the rails D' D' (on opposite sides of the tunnel) down 85 out of supporting contact with the wheels E, so that said rails can then be shoved forward in the direction of the length of the tunnel as far as may be needed. When in the building of the tunnel the stage and movable rails D' have been advanced sufficiently to permit 90 of the introduction of other permanent rails D in front of those already in place, the stage may be run back temporarily to put the new rails in place, as will be readily understood.

As it is very important to secure exact location of the traveling stage in lifting the me- 95

- talic lining-segments into place, I provide the stage with a rail-gripping device, which is shown at R in Fig. 2 and is shown in detail in Fig. 3. In a side frame C' of the stage I 5 mount two cross-bolts h h', of which the latter is fixed, while the bolt h turns in bearings and has right and left hand threads engaging corresponding threads in clamping-jaws H H, which are also guided on the bolt h'. The 10 screw-bolt h is provided with a hand-wheel h², by which it may be turned to advance the jaws H H toward each other to grip one of the rails or to move the jaws away from each other to free them from the rail.
- 15 I claim as my invention—
1. The combination of a tunnel-lining, supporting-brackets therein and two sets of rails on the brackets with a traveling stage having wheels to run on both sets of rails.
  - 20 2. The combination of a tunnel-lining, supporting-brackets therein and two sets of rails on the brackets with a traveling stage having wheels to run on both sets of rails and means for readily releasing one set of rails from 25 their supporting position to permit their longitudinal adjustment.
  - 25 3. The combination of a tunnel-lining, sup-

porting-brackets therein and two sets of adjacent rails on the brackets with a traveling stage having at each side wide wheels to run on the 30 two adjacent rails on that side.

4. The combination of a tunnel-lining, having supporting-brackets therein and two sets of rails on the brackets with a traveling stage having wheels to run on both sets of rails, 35 chairs for the rails and easily-removed transverse wedges to support one set of rails in the chairs.

5. A segment-erector for tunnel-linings, provided with a double-ended erector-bar and 40 means to move it lengthwise and also to turn it on a central axis.

6. The combination of a tunnel-lining and supporting-brackets therein with rails on the brackets, a traveling stage and a clamping device carried by the stage to grip one of the 45 rails.

In testimony whereof I have signed my name to this specification in the presence of two subscribing witnesses.

ERNEST W. MOIR.
